CONTROLLER MOUNTING FOR KNITTING MACHINES

Edward Vossen, Brooklyn, N. Y., assignor to Stop-Motion Devices Corp., Brooklyn, N. Y., a corporation of New York

Application February 17, 1945, Serial No. 578,536

11. Claims. (Cl. 66—157)

This invention relates to new and useful improvements in a controller mounting for a knitting machine. More particularly the new mounting is intended for a Wildman spring and latch needle knitting machine with a universal drive. However, similar constructions may be used on other knitting machines.

The new and improved controller mounting is used in combination with a controller or controller box having a horizontal shaft which turns a small angular distance when the controller is actuated. It is proposed to provide the horizontal shaft of the controller box with a lever having an offset end engaging in front of a horizontal finger which is indirectly mounted on a vertical rod turnably mounted on the main bracket of the universal drive of the knitting machine. This is the usual vertical rod on the Wildman machine which is associated with resilient means which tends to turn the rod a small angular distance in one direction for opening up the clutch of the universal drive, or for shifting the belt, depending upon its design.

It is proposed that a horizontal arm be mounted on the vertical rod and be provided with said horizontal finger which should be hingedly mounted to bend downwards and should normally be held in a horizontal position with resilient means, such as a leaf spring.

The invention contemplates forming said offset end of said lever with a cam face on its front side cooperative with said horizontal finger when the latter is moved backwards during the loading of the universal drive, to permit the horizontal finger to engage behind said offset end for accomplishing the "hold" of the loading action.

The invention also proposes the provision of means for tripping said horizontal finger downwards for releasing the vertical rod so that the universal drive is "declutched," that is so that the drive is uncoupled from the knitting machine.

The invention also contemplates a modified form in which a switch is provided for actuating the controller to release the horizontal arm so that "declutching" may take place, when the switch is actuated.

Still further the invention proposes the construction of a new and improved controller mounting, as briefly mentioned, which is exceptionally efficient and fast in operation and which may be manufactured and sold and installed at a relatively low cost.

For further comprehension of the invention, and of the objects and advantages thereof, reference will be had to the following description and ac-

companying drawing with respect to which reference is made to the figures of the drawing, in which Fig. 1 is a plan view of a controller mounting for a knitting machine constructed in accordance with this invention; Fig. 2 is a front elevational view of Fig. 1; Fig. 3 is a fragmentary enlarged vertical sectional view taken on the line 3—3 of Fig. 1; Fig. 4 is a side elevational view of a modified form of this invention; Fig. 5 is a plan view of Fig. 4. In the accompanying drawing forming a material part of this disclosure:

Fig. 1 is a plan view of a controller mounting for a knitting machine constructed in accordance with this invention.

Fig. 2 is a front elevational view of Fig. 1.

Fig. 3 is a fragmentary enlarged vertical sectional view taken on the line 3—3 of Fig. 1.

Fig. 4 is a side elevational view of a modified form of this invention.

Fig. 5 is a plan view of Fig. 4.

The new and improved controller mounting, in accordance with that form of the invention illustrated in Figs. 1 to 3 inclusive, is used in combination with the usual main bracket 10 of the universal drive of a Wildman spring and latch needle knitting machine or other similar machines. The bracket 10 is provided with bearings 11 which rotatively support the usual vertical rod 12 which is connected with resilient means tending to turn the rod 12 a small angular distance in one direction. This resilient means is associated with a radial arm 14 mounted on the vertical rod 12 and pivotally connected with a link 15 which in turn is pivotally connected with a block 16 slidably supported on a horizontal rod 17.

A pair of links 18 are pivotally connected with the sides of the block 16. These links 18 are pivotally connected on their other ends with radial arms 19 mounted on a rocker shaft 20 which is provided with a handle 21 by which the rocker shaft 20 may be conveniently turned. A spring 22 is coaxially mounted on the rod 17 and acts between the slideable block 16 and a stationary bracket 24, for urging the block 16 along the rod 17. The rocker shaft 20 is turnably supported in a part of said bracket 24. The spring 22 comprises the resilient means which tends to indirectly turn the rod 12 through a small angular distance. It also constitutes the spring which operates the clutch, or the belt shift for "declutching" the universal drive.

A horizontal arm 26 is mounted upon the rod 12 and is formed from two sections, namely a base section 27 which is fixedly mounted on the rod 12 and a horizontal finger 28 which is pivotally mounted upon the free end of the base section 27. The finger 28 is pivotally supported by a pintle 29. It is urged into a horizontal position by a leaf spring 31 which is mounted on the base section 27 and which acts against the finger 28 to urge the finger upwards. The finger 28 is pro-

vided with a shoulder 32 engageable against a portion of the base section 27 for limiting upwards pivoting of the finger 28 to said horizontal position, see Fig. 3.

A controller or controller box 33 is mounted by lugs 30 projecting from the controller box 33 and bolts 38 upon a strap 34 which is provided with a central stud 35 engaging into a boss 36 formed upon the top of the bracket 10. A set screw 37 firmly holds the stud 35 in position in the boss 36. The controller box 33 is provided with a horizontal shaft 39 which turns a small angular distance in one direction with the controller is actuated. In this particular case the controller box will turn a small distance counterclockwise. A controller box, which may be used for the controller box 33, is disclosed in my U. S. Letters Patent No. 2,357,713, granted on September 5, 1944, for a Controller for machines. The shaft 39 is provided with a handle 40 by which the controller box may be loaded. It is illustrated in its loaded position.

A lever 42 is mounted upon said horizontal shaft 39. This lever is in a horizontal position when the controller box is loaded. The lever 42 is provided with an offset end 43 which normally engages in front of the horizontal finger 28, for holding the vertical rod 12 from being turned by said spring 22. The front face 44 of the offset end 43 is curved and acts in the nature of a cam to cause the horizontal finger 28 to bend downwards when the rod 12 is turned and the horizontal finger 28 moves towards and against the offset end 43. In this way the horizontal finger 28 will slip down and around to the back of the offset end 43.

Means is provided for tripping the horizontal finger 28 downwards for releasing the vertical rod 12. This tripping means includes a bracket 46 mounted upon a bottom side corner of the controller box 33. A rod 47 is turnably mounted through the bracket 46. A collar 48 is mounted upon the rod 47 against one side of the bracket 46. A spring 49 is coaxially mounted on the rod 47 and acts between the collar 48 and a clip 50 mounted on the controller box 33. Another collar 51 is mounted on the rod 47 against the other end of the bracket 46. An arm 52 is mounted upon the collar 51 and extends across the bottom of the controller box 33 and up one side and terminates in a small hook portion 53 which is normally located immediately above the finger 28.

The spring 49 tends to hold the rod 47 in a turned position in which the hook portion 53 is just slightly above the top of the finger 28. The rod 47 has an offset end 55 to which a chain, or a flexible member may be connected, which when pulled downwards will cause the rod 47 to turn and correspondingly move the arm 52 so that the hook portion 53 will bend the finger 28 downwards and free from the offset end 43 of the lever 42. This bent end 55 may be connected with the hole detector chain which is supplied with the Wildman spring and latch needle knitting machine, or other knitting machine.

The controller box 33 is also provided with a bracket 57 which supports the usual conductor rod 58 which is connected with the electric circuit of the stop motion devices of the knitting machine. An insulation bushing 59 is interposed between the rod 58 and the bracket 57. An L-shaped strip of material 60 is attached by one of said bolts 38 with one of the ends of said strap 34. A transformer 63 is mounted upon and

supported by the strip 60. This is the usual transformer needed for the controller 33.

The bracket 10 is shown mounted upon the body 65 of the knitting machine. Details of the body 65 are not shown since the details of the knitting machine are not pertinent. The bracket 10 supports the usual drive shaft 66 which is provided with the usual brake drum 67. The drive shaft 66 may be driven by a belt drive, not shown, or any other drive.

The operation of the new and improved controller mounting may be understood from the following:

The block 16 is shown in a position in which the drive shaft 66 is connected with the drive motor, or other drive means. When the controller 33 is actuated, the lever 42 moves slightly angularly upwards and the offset end 43 will release the finger 28 freeing the vertical rod 12 so that the spring 22 may move the block 16 and disconnect the drive shaft 66 in the usual way. When the block 16 is moved, the link 15 and radial arm 14 will transmit the motion to turn the vertical rod 12, slightly clockwise in relation to a plan view of the rod 12. When the controller 33 was actuated, the horizontal shaft 39 turned slightly anticlockwise so as to move the offset end 43 upwards, and release the finger 28. The finger 28 may also be freed from the offset end 43 by the rod 47 when turned clockwise a small amount. When so turned, the arm 52 will move downwards so that the hook portion 53 depresses the finger 28. The finger 28 will bend downwards because it is pivotally mounted and is held in its horizontal position merely by the leaf spring 31.

The handle 21 may be actuated in the usual way, to reengage the clutch, or shift the belt so that the drive shaft is again driven. When the handle 21 is actuated it is turned counterclockwise so that the rocker shaft 20 turns, and turns the radial arms 19 moving the links 18 which in turn move the block 16 and compresses the spring 22. This action also turns the vertical rod 12 back to its loaded position. When the vertical rod 12 has been turned back to its loaded position, the handle 40 of the controller 33 may be turned clockwise to reload the controller, to move the lever 42 back to its horizontal position so that the offset end 43 is again in front of the horizontal finger 28. If the lever 42 is already in its horizontal position when the vertical rod 12 is turned back, the finger 28 will engage the cam surface 44 of the offset end 43 and will bend downwards, beneath the offset end 43 and then upwards in back of the offset end.

In Figs. 4 and 5 a modified form of the invention has been disclosed which is very similar to the prior form distinguishing merely in the fact that the controller box 33 is provided with a push button switch 70 for actuating the controller 33 for releasing the horizontal finger 28 in lieu of the rod 47, the arm 52 and the hook portion 53. A lever 71 is pivotally mounted at one end by a pintle 72 to a bracket 74 mounted on the bottom of the controller box 33. The lever 71 extends over the button of the push-button switch 70. The lever 71 may be connected with a chain, or other flexible member, or other connection and with the usual main stop motion controller of the Wildman spring and latch needle knitting machine, or other controller of any other type of knitting machine.

The operation of this form of the invention is identical to the prior form except for the fact that the lever 71 may be moved downwards to

operate the switch 70 which will operate the controller 33 in the usual way like any one of the stop motion switches which is used to operate said controller. With this arrangement, the need of a mechanical trip to press downwards the finger 28 has been eliminated.

In other respects this form of the invention is identical to the prior form and similar parts have been indicated by the same reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A controller mounting for a knitting machine, comprising a bracket, a vertical rod turnably mounted on said bracket, resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft and having an offset end engaging in front of said horizontal finger for holding said vertical rod from being turned by said resilient means.

2. A controller mounting for a knitting machine comprising a bracket, a vertical rod turnably mounted on said bracket, resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft and having an offset end engaging in front of said horizontal finger for holding said vertical rod from being turned by said resilient means, said horizontal arm being provided with a base portion which is fixedly mounted on said rod.

3. A controller mounting for a knitting machine comprising a bracket, a vertical rod turnably mounted on said bracket, a resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft and having an offset end engaging in front of said horizontal finger for holding said vertical rod from being turned by said resilient means, said horizontal arm being provided with a base portion which is fixedly mounted on said rod, and said horizontal finger being pivotally mounted on said base portion.

4. A controller mounting for a knitting machine comprising a bracket, a vertical rod turnably mounted on said bracket, resilient means tending to turn said rod a small angular distance in one direction, a horizontal arm mounted

on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft and having an offset end engaging in front of said horizontal finger for holding said vertical rod from being turned by said resilient means, said horizontal arm being provided with a base portion which is fixedly mounted on said rod, and said horizontal finger being pivotally mounted on said base portion, said horizontal finger having a shoulder engaging against said base portion for limiting upwards pivoting of the finger to its horizontal position.

5. A controller mounting for a knitting machine comprising a bracket, a vertical rod turnably mounted on said bracket, resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft and having an offset end engaging in front of said horizontal finger for holding said vertical rod from being turned by said resilient means, said horizontal arm being provided with a base portion which is fixedly mounted on said rod, and said horizontal finger being pivotally mounted on said base portion, said horizontal finger having a shoulder engaging against said base portion for limiting upwards pivoting of the finger to its horizontal position, said resilient means for holding said finger horizontally comprising a leaf spring mounted on said base section and engaging against the bottom of said horizontal finger.

6. A controller mounting for a knitting machine comprising a bracket, a vertical rod turnably mounted on said bracket, resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft and having an offset end engaging in front of said horizontal finger for holding said vertical rod from being turned by said resilient means, said offset end having a cam front face for forcing said horizontal finger downwards when said vertical rod is turned to move said horizontal finger backwards.

7. A controller mounting for a knitting machine, comprising a bracket, a vertical rod turnably mounted on said bracket, resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft having an offset end engaging in front of said horizontal finger for holding said vertical rod from being turned by said re-

silient means, and means for tripping said horizontal finger downwards.

8. A controller mounting for a knitting machine, comprising a bracket, a vertical rod turnably mounted on said bracket, resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft having an offset end engaging in front of said horizontal finger for holding said vertical rod from being turned by said resilient means, and means for tripping said horizontal finger downwards, comprising a turnably mounted rod connected with an arm having a hook portion engaging above said horizontal finger.

9. A controller mounting for a knitting machine, comprising a bracket, a vertical rod turnably mounted on said bracket, resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft having an offset end engaging in front of said horizontal finger for holding said vertical rod from being turned by said resilient means, and means for tripping said horizontal finger downwards, comprising a turnably mounted rod connected with an arm having a hook portion engaging above said horizontal finger, said rod having an offset end by which it may be easily turned.

10. A controller mounting for a knitting machine, comprising a bracket, a vertical rod turn-

ably mounted on said bracket, resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft having an offset end engaging in front of said horizontal finger for holding said vertical rod from being turned by said resilient means, and means for tripping said horizontal finger downwards, comprising a turnably mounted rod connected with an arm having a hook portion engaging above said horizontal finger, said rod having an offset end by which it may be easily turned, and resilient means for urging said rod into a position in which said hook portion is located immediately above said finger.

11. A controller mounting for a knitting machine, comprising a bracket, a vertical rod turnably mounted on said bracket, resilient means tending to turn said rod a small angular distance in one direction, a horizontal arm mounted on said rod and having a horizontal finger hingedly mounted to bend downwards, resilient means for holding said finger horizontally, a controller box mounted on said bracket and having a horizontal shaft which turns a small angular distance when the controller is actuated, and a lever mounted on said horizontal shaft having an offset end engaging in front of said horizontal finger for holding said vertical rod from being turned by said resilient means, a push button switch for electrically operating said controller and mounted on said controller box, a lever pivotally supported and extending across the button of said push button switch by which the switch may be actuated when the lever is pulled.

EDWARD VOSSEN.
